(57) CLAIM

The ornamental design for a case for mask, as shown and described.

DESCRIPTION

FIG. 1 is a front perspective view of a case for mask showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view of the case for mask shown in an alternate configuration with the cover in an opened condition;

FIG. 9 is a front view of FIG. 8;

FIG. 10 is a back view of FIG. 8;

FIG. 11 is a left side view of FIG. 8;

FIG. 12 is a right side view of FIG. 8;

FIG. 13 is a top plan view of FIG. 8;

FIG. 14 is a bottom plan view of FIG. 8; and,

FIG. 15 is an exploded view of the case for mask shown in an environment of use with a mask.

The broken lines depict portions of the case for mask that form no part of the claimed design. The broken line showing of a mask in FIG. 15 depicts environmental structure only and forms no part of the claimed design.

1 Claim, 15 Drawing Sheets
